STEREO-TAPE PLAYER

Robert P. Maniaci, Downey, Calif., assignor to California
Auto Radio Inc., Downey, Calif.

Filed Mar. 9, 1970, Ser. No. 21,798

Term of patent 14 years

Int. Cl. D14—03

U.S. Cl. D26—14

FIG. 1.

FIG. 2.

FIG. 3.

FIG. 4.

FIG. 5.

FIG. 1 is a front perspective view of a stereo tape player appliance embodied in a stereo tape player wherein the back is conventionally plain;

FIG. 2 is a front elevation thereof;

FIG. 3 is a side elevation thereof, the undisclosed opposite side being a mirror image of the side shown;

FIG. 4 is a front perspective view of a modified form of the appliance illustrated in FIG. 1 wherein said form is embodied in a combined radio and stereo tape player; and

FIG. 5 is a front elevation thereof.

I claim:

The ornamental design for a stereo-tape player, substantially as shown and described.
